Primary Examiner — Phillip S Hyder(74) *Attorney, Agent, or Firm* — Jason P. Mueller; Adams and Reese LLP(57) **CLAIM**

The ornamental design for a knife, as shown and described.

DESCRIPTION

Pursuant to 35 U.S.C. 119(a), the instant application is a divisional of U.S. Design application Ser. No. 29/423,751 filed on Jun. 5, 2012, claiming priority to prior Application Number DM/077268 WIPO, filed Dec. 7, 2011.

FIG. 1 is a perspective view of a knife showing our new design;

FIG. 2 is a front elevation view thereof;

FIG. 3 is a rear elevation view thereof, in an inverted position;

FIG. 4 is an enlarged top plan view of the knife of FIG. 1;

FIG. 5 is an enlarged bottom plan view thereof;

FIG. 6 is a right side elevation view thereof; and,

FIG. 7 is a left side elevation view thereof.

The broken line showing of the blade is included for the purpose of illustrating environmental structure that forms no part of the claimed design.
